UNITED STATES PATENT OFFICE.

JOHN SOLOMON HEELEY, OF GALLATIN, PENNSYLVANIA.

ENVELOP.

1,024,258.

Specification of Letters Patent. Patented Apr. 23, 1912.

Application filed January 24, 1911. Serial No. 604,414.

To all whom it may concern:

Be it known that I, JOHN SOLOMON HEELEY, a subject of the King of Great Britain, residing at Gallatin, in the county 5 of Allegheny and State of Pennsylvania, have invented certain new and useful Improvements in Envelops, of which the following is a specification, reference being had therein to the accompanying drawing.

10 This invention relates to envelops, and the objects of my invention are to furnish an envelop with positive and reliable means in a manner as will be hereinafter set forth whereby the contents of the envelop cannot 15 be surreptitiously removed without detection, and to provide an envelop that can be advantageously used for transmitting valuable matter by mail or express.

Further objects of the invention are to 20 provide an envelop with a novel lining that will further frustrate the efforts of a person from fraudulently removing the contents of the envelop and to accomplish the above results by an envelop that is simple in construction, durable, easy to seal and inexpensive to manufacture.

With the above and such other objects in view as may hereinafter appear, the invention 30 consists of the novel construction, combination and arrangement of parts to be presently described in detail and then claimed.

Reference will now be had to the drawing, wherein:—

35 Figure 1 is a plan of a blank from which the envelop is made, Fig. 2 is a plan upon a smaller scale of a lining for the envelop, Fig. 3 is a plan of the envelop sealed, Fig. 4 is a longitudinal sectional view of the 40 same, and Fig. 5 is a cross sectional view.

An envelop in accordance with this invention comprises a rectangular body 1 having triangular-shaped end flaps 2 adapted to be folded upon the dotted lines 3. The lower 45 edge of the body 1 is provided with a bottom flap 4 adapted to be folded upon the dotted line 5 on to the body 1 and the end flaps 2, the edges of the bottom flap 4 being gummed or provided with adhesive material 6, which 50 when moistened, will cause the bottom flap 4 to adhere to the lower angular edges of the end flaps 2. Centrally of the bottom flap 4 are two longitudinal slits 7 providing a longitudinal strap 8, the purpose of which will

presently appear. The upper edge of the 55 body 1 is provided with a sealing flap 9 adapted to be folded upon the dotted line 10, said sealing flap having the edges thereof gummed or provided with adhesive material 11.

60 The envelop blank is provided with a lining, preferably made of light tissue paper whereby the weight of the envelop will not be materially increased for mailing purposes. The tissue paper lining comprises a 65 rectangular body 12 corresponding in area to the body 1, said body having end flaps 13, a bottom flap 14 and a top flap 15. The top flap 15 is provided with a tongue 16, perforations 17 and adhesive material 18. 70 The bottom flap 14 is gummed or provided with adhesive material 19, and after the end flaps 13 have been folded upon the body 12, the bottom flap 14 is secured through the medium of the adhesive material 19 to the 75 end flap 13. The tissue paper envelop thus formed is inserted in the main envelop and is in condition to receive the matter to be inclosed.

Assuming that the matter has been placed 80 within the envelop, the top flap 15 of the lining is folded, the tongue 16 moistened and inserted under the strap 8 of the bottom flap 4 of the main envelop. Pressure upon the outer side of the tongue 16 causes said 85 tongue to adhere to the outer side of the bottom flap 4. The sealing flap 9 of the envelop can then be moistened and closed, and caused to adhere to the flaps 2, 4 and 5, the sealing flap 9 being slightly larger than 90 the top flap 15, whereby the edges of the sealing flap 9 will overlap the edges of the top flap 15. As a further precaution against unauthorized opening of the envelop, the sealing flap 9 is provided with a series of 95 perforations 20 adjacent to the edges thereof, and these perforations coöperate with the perforations 17 of the top flap 15 in detecting 100 any tampering with the envelop.

From the foregoing it will be observed 100 that I have devised an inclosure which is practically one envelop within another, the two envelopes being arranged whereby it is impossible for the contents of the inner envelop being obtained without some portion of the inner envelop or outer envelop 105 being marred or injured.

The outer envelop can be made of paper,

paperoid and a suitable light material can be used in lieu of tissue paper for the inner lining or envelop.

What I claim is:—

- 5 An envelop comprising a body, end flaps carried thereby and adapted to be folded upon said body, a bottom flap carried by the lower edge of said body and adapted to be adhesively connected to said end flaps, said 10 bottom flap having longitudinal slits providing a strap, a lining for said envelop comprising a body, end flaps and a bottom flap adapted to be adhesively connected to said end flaps to provide an inclosure for 15 matter, said lining further including a top flap having a tongue provided with perfora-

tions and gummed and capable of being passed under said strap and adhesively secured to said bottom flap, and a sealing flap carried by the envelop body and provided with perforations and adhesive material whereby said sealing flap can be adhesively connected to the top flap and tongue of said lining and to the end flaps and bottom flap of the first envelop body, substantially as, 20 and for the purpose herein described. 25

In testimony whereof I affix my signature in the presence of two witnesses.

JOHN SOLOMON HEELEY.
